ATTORNEY

UNITED STATES PATENT OFFICE.

CARL HJALMAR LARSSON, OF SEATTLE, WASHINGTON.

PHONOGRAPH-HORN.

1,323,777.

Specification of Letters Patent.

Patented Dec. 2, 1919.

Application filed November 22, 1918. Serial No. 263,642.

To all whom it may concern:

Be it known that I, CARL HJALMAR LARSSON, a subject of the King of Sweden, and resident of the city of Seattle, county of King, and State of Washington, have invented certain new and useful Improvements in Phonograph-Horns, of which the following is a specification.

My invention relates to phonographs and like machines used for reproducing sounds through the medium of a record and consists of an apparatus to be attached to the tone arm of a machine and to serve the same purpose as the horn, namely, to amplify the sound and modify its tone.

The object of my invention is to produce a device of this sort which would ordinarily be installed in the cabinet or case upon which the phonograph is supported and which will improve both the volume of sound and quality of tone.

The features of novelty in my invention will be hereinafter described and then particularly defined in the claim.

In the accompanying drawings I have shown the same embodied in the type of construction which I now prefer.

Figure 1 is a vertical section or elevation of my device.

Fig. 2 is an elevation, in partial section, of the same.

As I have shown the device in the drawings, it is embodied within a casing 1, which casing may be constructed in any suitable or desired manner. This is illustrated as a plain casing. It may be given all the ornamentation desired. The phonograph A is mounted upon the upper end of this casing. The tone arm 10 is connected to an opening 11 in the upper end wall of the casing. A tube 2 is connected with this opening 11 and extends downward within the casing to a connection to the upper end of the tapered horn section 3.

This horn section 3 is made of flattened cross section; that is, it is much wider in one direction than the other. It is drawn to a small size at the point where it connects with the tube 2 and is expanded therefrom so that in one direction it is in width the same as that of the casing. This is indicated by the dotted lines in Fig. 2. In the other way, or as shown in cross section in Fig. 1, it expands to a size somewhat less than half the width of the casing in this direction.

The lower edge of this section 3 is supported at one side from a ledge 40 which is carried by the lower edge of a diaphragm 4, which diaphragm is preferably made as a wide board which extends entirely across the case or cabinet, and which is close to, but not directly in contact with, the adjacent side of the horn 3. The intention is that the walls of the horn shall be entirely disconnected from all parts of the casing to as full an extent as feasible.

The lower edge of this horn section, at the opposite side, is supported from the side wall of the casing, as by means of a strip 30, which is secured to the casing and upon which the lower edge of this wall of the horn rests. The lower edges of the horn are preferably fixed in position by gluing.

A return bend extension of the horn is formed by a diaphragm 5 which extends in a curve from the strip 30, around to a connection with the opposite wall of the case or cabinet 1. This diaphragm is preferably made of thin wood veneer, which veneer is preferably of a compound construction, that is, of a plurality of layers which are glued together, these layers being so disposed that the grain of adjacent layers cross.

The diaphragm 5 should be placed at such an elevation that its central portion does not contact with the bottom of the casing. Its side edges extend, however, to the side walls of the casing. The intention is to mount this diaphragm in such way that its resonance and the vibrations produced by the sounds, will not be interfered with. This diaphragm will be fixedly secured only at its ends, that is, to the side walls of the casing. Before insertion in the device it is in flat condition and will be sprung into place when inserted. It is, therefore, under tension.

The board 4, which forms a diaphragm extending across the casing, I prefer to secure to the side walls by means of glue and dowel pins, as 41. The purpose of this form of construction is to secure a resonant condition in all parts of the structure and to have no nails or anything of that nature used where it can well be avoided and thus to prevent interference with the tonal and resonant qualities of the construction.

Extending from the upper edge of the board 4 is another curved diaphragm 6. This diaphragm is preferably of the com-

pound veneer construction described as being employed for the diaphragm 5. It is also sprung into position in a similar manner. It connects the upper edge of the board 4 with the upper edge of an opening 12 in the front side face of the casing. It thus forms a deflector for the sound.

At its upper edge this is secured in place by resting in a notch formed by the strip 60 10 and the front wall of the casing. At its lower edge it is inset into a notch formed at 42 in the upper edge of the board 4. It may be securely fixed therein by gluing. This diaphragm is thus of such a construction 15 that it is highly resonant and also has good tonal qualities.

At the front side of the casing I prefer to employ another diaphragm 8, which diaphragm extends from the upper forward 20 edge of the curved diaphragm 5, upwardly to a point even with the lower edge of the opening 12 in the case. This diaphragm 8 is mounted so as to be slightly removed from the casing 1, so that it is free to vibrate.

25 The construction above described forms what may be called a horn, which has two sections lying substantially parallel with each other and connected by a return bend section. The cross sectional area of all parts 30 of this horn, as herein illustrated, is of a rectangular or quadrilateral outline. It is also, as illustrated, of greater dimensions in one direction than at right angles thereof.

By reason of these facts it may be installed 35 within a cabinet which may be used as a support for the phonograph and be of a greater size than may be conveniently otherwise employed. It is thus possible to get a volume of sound which could not 40 otherwise be obtained and also, by reason of its size and the manner of constructing and supporting the side walls of the horn, to get a softness of tone and a quality which is otherwise difficult to obtain.

45 In this connection I prefer to employ,

for the tube 2, which connects the upper end of the horn proper with the tone arm, some nonresonant material, as for instance, lead pipe. I have found that the use of a tube of this character at this point cuts out much 50 of the scratchy sound often found in phonographic music. The cabinet may be provided with a recess or well at the point 13, for the reception of the motor and the apparatus by which the disk-carrying turntable is operated.

What I claim as my invention is:

A sound amplifying device for phonographs comprising a cabinet, an initial horn section of tapering or pyramidal form having 60 its base coextensive in one direction with the width of the cabinet and flattened in the other direction to less than half the width of the cabinet, the cabinet having a partition board upon the lower edge of which the 65 inner base edge of one long side of the pyramid is supported, the opposite side of the said pyramidal section extending farther and being supported from a side wall of the cabinet, a semi-cylindrical diaphragm extending 70 from the end of said latter side of the initial section and at its other end being supported from the opposite side wall of the cabinet and intermediate these points being out of contact with the cabinet, said 75 curved diaphragm extending laterally clear across the cabinet, a diaphragm extending from the end of the said curved diaphragm substantially tangent thereto and spaced from the adjacent wall of the cabinet, a 80 curved diaphragm extending from the upper edge of the partition board and curving over with its outer end substantially in alignment with the said tangentially placed diaphragm and separated from the edge 85 thereof to form a mouth for the amplifying horn.

Signed at Seattle, Washington, this 14th day of November, 1918.

CARL HJALMAR LARSSON.
